HOLDER

Carl F. Anderson, St. Paul, Minn.

Application January 2, 1940, Serial No. 311,991

10 Claims. (Cl. 51—194)

This invention has relation to a holder for a strip of material adapted to be employed for abrading or polishing purposes, as, for example, a strip of abrasive or emery cloth or paper, or a strip of felt, etc. More explicitly, the invention relates to a cylindrical holder designed to be mounted for rotation and adapted removably to retain a strip of abrading or polishing material about and in firm and close engagement with its periphery.

An object of the invention is to provide a holder of the present type which will be of novel and improved construction.

A further object is to provide a holder, for removably retaining a strip of material adapted to be employed for abrading or polishing purposes, wherein will be incorporated various improved features and characteristics of construction novel both as individual entities of the holder and in combination with each other.

And a further object is to provide a cylindrical holder, designed to be mounted for rotation and adapted removably to retain a strip of abrading or polishing material, which will be of simple construction and can be inexpensively manufactured.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification:

Fig. 1 is an end elevational view, partially broken away, of a holder made according to the invention;

Fig. 2 is a central sectional view of the holder, taken on line 2—2 in Fig. 1;

Fig. 3 is an enlarged fragmentary view detailing features of the invention, disclosing elements at the upper portion of the illustrations of Figs. 1 and 2 as said elements would appear from the position designated by line 3—3 in said Fig. 2 with the adjacent half or part of the shell of the holder removed and with a strip of abrading or polishing material applied upon or to the periphery of the opposite half or part of said shell of said holder;

Fig. 4 is a view corresponding with the disclosure of Fig. 3, but showing the movable or rotatable tightening and fastening device of the holder in one of its inoperative positions;

Fig. 5 is an elevational view of said movable or rotatable tightening and fastening device as when removed from the remainder of the holder;

Fig. 6 is an elevational view, partially in section and partially broken away, of the stationary tightening and fastening device of the holder as when removed from the remainder of said holder; and

Fig. 7 is a transverse sectional view of said stationary tightening and fastening device, taken as on line 7—7 in Fig. 6.

With respect to the drawing and the numerals 10 of reference thereon, the novel and improved holder includes a cylindrical shell 10 constituted as opposite, complementary, hollow halves or parts each consisting of an annular base 11 and a cylindrical skirt portion 12 upon and integral with and perpendicular to said annular base. To provide the cylindrical shell 10 the complementary halves or parts thereof are secured rigidly to each other, in a manner to be set forth, with the marginal edges 13 of the skirt portions 12 in abutting engagement. The outer cylindrical surface of each skirt portion 12 is covered by a piece 14 of leather, or other flexible element or substance, and the adjacent margins or edges 15 of the different pieces 14 desirably are in abutting relation when the halves or parts of the cylindrical shell 10 are assembled together. Stated otherwise, the pieces 14 of leather, or equivalent, together provide a complete covering for both skirt portions 12, and said pieces 14 are rigidly secured upon or to the outer cylindrical surfaces of said skirt portions 12. The marginal edges 13 are parallel with the annular bases 11, and said bases are perpendicular to the axis for the holder passing through the bases. Spaced bearings for rotatably supporting the holder are provided by spaced openings, denoted 16, 16, arranged centrally in the annular bases 11, 11, respectively. Said spaced bearings or openings 16, 16 are concentric with the cylindrical skirt portions 12 of the holder when assembled, and provide means through the instrumentality of which said holder can be fixed in any suitable and convenient manner upon a shaft or member adapted to be rotated.

In the disclosure as made, a hollow connector tube 17 is disposed in surrounding relation to the spaced or opposite bearings 16, 16, and the opposite ends, respectively, of said connector tube integrally carry spaced extension lugs 18 which are imbedded in and secured in slots in the annular bases 11. The hollow connector tube 17 is perpendicular to said annular bases 11, and constitutes means at the central portion of the holder designed to the purpose of retaining the two halves or parts of the cylindrical shell 10 in fixed relation to each other. The opposite ends of the connector tube 17 in the illustrated embodiment of the invention are in engagement with the inner or adjacent surfaces, respectively, of the annular bases 11.

A stationary tightening and fastening device of the holder is constituted as a hollow cylindrical element 19 fixedly supported by and between the annular bases 11 of said holder and situated at a side of the hollow connector tube 17 in slightly spaced relation to the circumference of perimeter of the hollow cylindrical shell 10, provided by the two skirt portions 12 and the two pieces 14 of leather, or equivalent. Said hollow cylindrical element 19 integrally carries spaced extension lugs 20 upon its opposite ends, respectively, which are imbedded in and secured in slots in the annular bases 11. The hollow cylindrical element 19 is parallel with the hollow connector tube 17, as well as perpendicular to the annular bases 11, and constitutes means at one side of the holder designed to the purpose of retaining the two halves or parts of the hollow cylindrical shell 19 in fixed relation to each other. The opposite ends of the stationary tightening and fastening device or hollow cylindrical element 19 as disclosed are in engagement with the inner or adjacent surfaces, respectively, of the annular base 11.

The side of said stationary tightening and fastening device or hollow cylindrical element 19 which is adjacent to the circumference or perimeter of said cylindrical shell 10 is cut away to provide a clearance or passageway 21 extending longitudinally of said device or element 19 for the width of the hollow cylindrical shell, and said circumference or perimeter of the hollow cylindrical shell; or, more explicitly, the skirt portions 12 and the pieces 14 of leather, or equivalent, which provide said circumference or perimeter; is cut away at location directly adjacent the clearance or passageway 21 to provide a clearance or passageway 22 also extending longitudinally of the device or element 19 for the width of said hollow cylindrical shell and disposed in alining, 40 relation to said clearance or passageway 21 in direction radially of said hollow cylindrical shell. That is, the clearances or passageways 22 and 21 provide for access to the interior of the stationary tightening and fastening device or hollow cylindrical element 19, to a purpose which presently will be made to appear.

A movable or rotatable tightening and fastening device of the holder is situated within the hollow cylindrical element 19 and is supported by the bases 11 of the holder. More explicitly, the movable or rotatable tightening and fastening device is constituted as a cam including a shaft 23 thereof having its opposite ends 24 rotatably mounted in the annular bases 11, 11, respectively, and an eccentric portion 25 thereof integral or rigid with said shaft 23. As illustrated, the eccentric portion 25 of said cam has length substantially equal to the distance between the spaced apart annular bases 11. Stated otherwise, said eccentric portion of the cam extends the full distance between the annular bases 11 and is parallel with the hollow cylindrical element 19. The shaft 23 of the cam, including the end portions 24 of said shaft, is situated concentrically of said hollow cylindrical element 19 and is perpendicular to the bases 11, 11 of the hollow cylindrical shell 10. Both ends 24 of the shaft 23 are accessible at the outer sides of the bases 11, and at least one of said ends 24 is provided with an angular or squared opening 26 for receiving a wrench or other tool adapted to be employed to rotate the cam upon its axis.

In order that the holder will be nicely balanced when fixed, as by employment of the spaced bear-

ings 18, upon a shaft adapted to be rotated, said holder includes a counterweight or balance weight 27 which is disposed within the hollow cylindrical shell 10 at the side thereof directly opposite the stationary tightening and fastening device and the movable or rotatable tightening and fastening device. Said weight 27 in the illustrated embodiment of the invention is constituted as a solid block integrally carrying annular extension lugs 28 upon its opposite ends, respectively, which are imbedded in and secured in annular openings in the annular bases 11. The weight or block 27 is parallel with and in spaced relation to the hollow connector tube 17, as well as perpendicular to the annular bases 11, and constitutes means at the side of the holder opposite the stationary tightening and fastening device and the movable or rotatable tightening and fastening device designed to the purpose of retaining the two halves or parts of said hollow cylindrical shell 10 in fixed relation to each other. The opposite ends of the weight or block 27 as disclosed are in engagement with the inner or adjacent surfaces, respectively, of the annular bases 11.

25 The stationary tightening and fastening device, constituted as the hollow cylindrical element 19, and the movable or rotatable tightening and fastening device, constituted as the cam including the shaft 23 and the eccentric portion 25, together comprise complementary means of the holder designed and adapted, the one in co-operation with the other, to cause a strip of material 29, adapted to be employed for abrading or polishing purposes, such as a strip of abrasive or emery cloth or paper, or a strip of felt, etc., to be tightened about and removably fastened down against the circumference or perimeter of the hollow cylindrical shell 10.

30 Any strip of material, such as the strip 29, to be tightened and removably fastened upon the circumference or perimeter of said hollow cylindrical shell 10 normally will have free opposite end portions 30. In practice, a roll of material suitable for abrading or polishing purposes desirably will be provided, and strips of material, such as the strip 29, each of length suitable to the purpose, separately will be removed or torn from said roll of material to be useful for application to the hollow cylindrical shell 10 of the holder.

35 The hollow cylindrical element 19 provides a longitudinal bore 31 defined by an internal cylindrical surface 32 of said hollow cylindrical element, and the cam including the shaft 23 and the eccentric portion 25 is situated within said longitudinal bore in such manner that an external cylindrical surface 33 of said eccentric portion is always in comparatively close, but spaced, relation to said internal cylindrical surface 32 of the hollow cylindrical element 19, no matter to what position said shaft 23 and the cam may be rotated. More explicitly, the external cylindrical surface 33 of the eccentric portion 25 is the part of said eccentric portion which is farthest from the shaft 23, and is adapted to rotate, with turning movement of said shaft, within the longitudinal bore 31 while spaced at distance from the internal cylindrical surface 32 of said hollow cylindrical element 19 a trifle less than a measurement representing double the thickness of a strip of material, such as 29, to be tightened about and fastened down against the circumference or perimeter of the hollow cylindrical shell 10.

When a strip of material, such as 29, is to be tightened and removably fastened upon the holder, said strip is placed snugly about the circumference or perimeter of the hollow cylindrical shell 10 of said holder and the free opposite end portions 30 of the strip, the one superimposed upon the other, are inserted through the clearances or passageways 22 and 21 into the longitudinal bore 31 of the hollow cylindrical element 19, at either side of the shaft 23 and the eccentric portion 25 constituting the cam, about as disclosed in Fig. 4. Then said cam is rotated, in the direction of the arrow, from a releasing position, as in said Fig. 4, to its fastening position, as in Fig. 3. It will be evident that with rotation of the cam to the position as in said Fig. 3, from the neighborhood of said cam as in Fig. 4, the external cylindrical surface 33 of the eccentric portion 25 will cause the superimposed free opposite end portions 30 of the strip 29 of material to be grasped between the internal cylindrical surface 32 of the hollow cylindrical element 19 and said external cylindrical surface of said eccentric portion and moved from the position of said free opposite end portions as in said Fig. 4, where the strip of material is more or less loose upon the circumference or perimeter of the hollow cylindrical shell 10, to the position of the free opposite end portions as in Fig. 3, where said strip of material is tightly fastened about and upon said circumference or perimeter of said hollow cylindrical shell. That is, with rotation of the cam to the position as in Fig. 3, the eccentric portion 25 will push the free opposite end portions 30 of the strip of material up against the internal cylindrical surface 32 of the hollow cylindrical element 19 and cause said free opposite end portions to be slid over said internal cylindrical surface to the position as in said Fig. 3, so that said strip of material will be made taut, or stretched, upon the circumference or perimeter of the hollow cylindrical shell 10. Evidently, while being moved from their position as in Fig. 4 to their position as in Fig. 3, the free opposite end portions 30 will slide over the spaced apart, oppositely disposed surfaces 34 which define the side walls of the clearance or passageway 22. In Fig. 3 the external cylindrical surface 33 of the eccentric portion 25 is at the side of the shaft 23 directly opposite the clearance or passageway 21 to cooperate with said internal cylindrical surface 32 to cause said free opposite end portions 30 to be securely, but removably, fastened within the longitudinal bore 31. It will be evident that upon rotation of the cam in either direction from its position as in Fig. 3, the strip of material will be released. Rotation of said cam in direction opposite that indicated by the arrow in said Fig. 3 actually will cause the end portions 30 partially to be ejected from the bore 31. It also will be evident that the free opposite end portions 30 could be inserted in the longitudinal bore 31 at the side of the cam opposite that in which shown in Fig. 4, and said cam then rotated in direction opposite that indicated by the arrow to tighten up and fasten the strip of material 29.

The external cylindrical surface 33 of the eccentric portion 25 is provided with spaced apart, outwardly extending protuberances 35, and the internal cylindrical surface 32 of the hollow cylindrical element 19 is provided with spaced apart, inwardly and circumferentially extending protuberances 36. Said protuberances 35 are for the

purpose of insuring that rotation of said eccentric portion 25 positively will cause the free opposite end portions of the strip of material, such as 29, together to be slid over the internal cylindrical surface 32 of the hollow cylindrical element 19 with movement of the cam to its position as in Fig. 3, say from its position as in Fig. 4, and said protuberances 35 and 36, in cooperation with each other, are for the purpose of insuring that said free opposite end portions of the strip of material will be fastened stably against the possibility of accidental removal from or displacement in the holder when the parts of said holder are situated as in said Fig. 3.

More explicitly, there are two spaced apart, longitudinally extending rows of spaced apart protuberances 35, each row, as disclosed, including three spaced apart protuberances. The two longitudinally extending rows of protuberances 35 are in comparatively close relation to each other, and said rows are at opposite sides of a plane passed diametrically through each of the hollow cylindrical element 19, the shaft 23 and the hollow cylindrical shell 10. Protuberances 35 in the different rows are directly opposite each other. There are, in the illustrated embodiment of the invention, two spaced apart, circumferentially extending protuberances 36, both at the side of the hollow cylindrical element 19 directly opposite the clearance or passageway 21, including a circumferentially extending protuberance 36 situated between each pair of adjacent protuberances 35 of each longitudinal row of protuberances 35 upon the eccentric portion 25. That is to say, each circumferentially extending protuberance 36 is so located upon the internal cylindrical surface 32 of the hollow cylindrical element 19 that it will be between and in spaced relation to a plurality of protuberances 35 upon the eccentric portion 25 when said hollow cylindrical element and said eccentric portion are relatively positioned as in Fig. 3. Stated differently, when the parts are situated as in said Fig. 3, there is, in the disclosure as made, at least one protuberance 35 between and in spaced relation to a plurality of circumferentially extending protuberances 36, and at least one circumferentially extending protuberance 36 between and in spaced relation to a plurality of protuberances 35. Preferably, the circumferentially extending protuberances 36 will be of length to extend at least the distance between the two spaced apart rows of protuberances, and, desirably, said protuberances 36 may terminate beyond both rows of protuberances 35.

It will be apparent that the protuberances 35 can be sharp-edged, or of nature to penetrate or enter the material of the free opposite end portions 30 of a strip such as 29, so that with rotational movement of the eccentric portion 25 toward and to the position as in Fig. 3 both of said free opposite end portions positively will be caused to be slid over the internal cylindrical surface 32 of the hollow cylindrical element 19. That is, the construction and arrangement can be such that the protuberances 35 will stick into the free opposite end portions 30 a sufficient distance to cause both of said end portions bodily to be carried by said protuberances 35 as these protuberances are moved or rotated toward and to their position as in Fig. 3. That the protuberances 35 may penetrate or enter both or either of the free opposite end portions 30 is of no moment insofar as marring of the material of a strip, such as 29, is concerned, because each strip

of material employed upon the holder is intended to have but a single use. Stated differently, each strip of material, such as 29, removed from the holder after performing its intended service ordinarily is discarded.

Also it will be apparent that the protuberances 35 and 36, in cooperation with each other, as well as with the external cylindrical surface 33 of the eccentric portion 25 of the cam and the internal cylindrical surface 32 of the hollow cylindrical element 19, will confine and limit the free opposite end portions 30 of the strip of material when inserted and fastened in the holder as in Fig. 3 against the possibility of accidental removal from or displacement in said holder. Clearly, during rotational movement of the eccentric portion 25 toward and to the position as in Fig. 3 from the neighborhood in which said eccentric portion is shown in Fig. 4 the protuberances 35 will cause the free, opposite, superimposed end portions 30 to be slid over the circumferentially extending protuberances 36, and when the eccentric portion has reached its position as in said Fig. 3, the protuberances 35 and 36 will, in cooperation with each other, cause said end portions tightly to be grasped between said protuberances 35 and 36, as well as between the cylindrical surfaces 33 and 32 supporting the protuberances. In practice, the inner surfaces of the circumferentially extending protuberances 36 desirably will terminate in a circumference somewhat within that of the end portion 30 which is outermost when the strip of material is fastened as in Fig. 3, so that the protuberances 35 and 36 will cause the free opposite end portions 30 to be crimped, or include a wave, when secured in the holder. In order that the protuberances 35 can cause said free opposite end portions 30 readily to be slid over the circumferentially extending protuberances 36 these latter protuberances merge smoothly at their opposite end portions 37 into the internal cylindrical surface 32 of the hollow cylindrical element 19.

In some instances it might be desirable to set the external cylindrical surface 33 at location from the internal cylindrical surface 32 equal at least to the combined thickness of the superimposed end portions 30. In any event, the protuberances 35 and 36, when employed, will cause said end portions 30 to be confined under pressure between said protuberances.

What is claimed is:

1. A holder comprising a member providing an outer circumferential surface, said member including a bore providing an internal cylindrical surface having an inwardly extending protuberance thereon and there being a passageway leading from said outer circumferential surface to said bore, and a cam adapted to be actuated within said bore, the outer circumferential surface of said member being adapted to receive a strip of material to be fastened about and upon said outer circumferential surface, and superimposed portions of said strip of material being adapted to be inserted through said passageway into said bore at a side of said cam, the cam including an external cylindrical surface thereof having an outwardly extending protuberance thereon adapted to be rotated in proximate relation to the internal cylindrical surface of said bore to pull said superimposed portions of the strip of material inwardly of said bore thus to cause said strip to be made taut upon said outer circumferential surface, and the protuberances upon said external and internal cylindrical sur-

faces in cooperation with each other being adapted to cause said superimposed portions of the strip removably to be fastened in said holder.

2. A holder comprising a hollow shell providing an outer circumferential surface and spaced apart end walls, a hollow tubular element extending between and mounted in said end walls and providing a bore defined by an internal cylindrical surface of said hollow tubular element, there being a passageway leading from said outer circumferential surface through said hollow tubular element to said bore, and a cam adapted to be actuated within said bore, the outer circumferential surface of said shell being adapted to receive a strip of material to be fastened about and upon said outer circumferential surface, and superimposed portions of said strip of material being adapted to be inserted through said passageway into said bore at a side of said cam, the cam including portions thereof mounted in said end walls, respectively, and an external cylindrical surface thereof adapted to be rotated in proximate relation to the internal cylindrical surface of said hollow tubular element.

3. The combination as specified in claim 2, and bearings upon said spaced apart end walls concentric with said outer circumferential surface for rotatably mounting said shell.

4. The combination as specified in claim 2, 30 bearings upon said spaced apart end walls concentric with said outer circumferential surface for rotatably mounting said shell, said hollow tubular element and cam being at a side of said bearings adjacent the outer circumferential surface of said shell, and a counterweight supported by said hollow shell at the side of said bearings opposite said hollow tubular element and cam.

5. The combination as specified in claim 2, 40 bearings upon said spaced apart end walls concentric with said outer circumferential surface for rotatably mounting said shell, said hollow tubular element and cam being at a side of said bearings adjacent the outer circumferential surface of said shell, a counterweight supported by 45 said end walls at the side of said bearings opposite said hollow tubular element and cam, and a connector member extending between said end walls.

6. A holder comprising a hollow shell providing 50 an outer circumferential surface and spaced apart end walls, a hollow tubular element extending between and mounted in said end walls and providing a bore defined by an internal cylindrical surface of said hollow tubular element, 55 there being a passageway leading from said outer circumferential surface through said hollow tubular element to said bore, and a cam adapted to be actuated within said bore, the outer circumferential surface of said shell being adapted to receive a strip of material to be fastened about and upon 60 said outer circumferential surface, and superimposed portions of said strip of material being adapted to be inserted through said passageway into said bore at a side of said cam, the cam including portions thereof mounted in said end walls, respectively, and an external cylindrical surface thereof adapted to be rotated in proximate relation to the internal cylindrical surface of said hollow tubular element to pull said superimposed portions of the strip of material inwardly of 70 said hollow tubular element thus to cause said strip to be made taut upon said outer circumferential surface and said external and internal surfaces of said cam and said hollow tubular element, respectively, in cooperation with 75

each other being adapted to cause said superimposed portions of the strip removably to be fastened in said holder.

7. A holder comprising a member providing an outer circumferential surface, said member including a bore providing an internal cylindrical surface and there being a passageway leading from said outer circumferential surface to said bore, a cam adapted to be actuated within said bore, the outer circumferential surface of said member being adapted to receive a strip of material to be fastened about and upon said outer circumferential surface, and superimposed portions of said strip of material being adapted to be inserted through said passageway into said bore at a side of said cam, the cam including an external cylindrical surface thereof adapted to be rotated in proximate relation to the internal cylindrical surface of said bore to pull said superimposed portions of the strip of material inwardly of said bore thus to cause said strip to be made taut upon said outer circumferential surface, and said external and internal cylindrical surfaces in cooperation with each other being adapted to cause said superimposed portions of the strip removably to be fastened in said holder and complementary protuberances upon the external cylindrical surface of said cam and the internal cylindrical surface provided by said bore.

8. A holder comprising a member providing an outer circumferential surface, said member including a bore providing an internal cylindrical surface and there being a passageway leading from said outer circumferential surface to said bore, a cam adapted to be actuated within said bore, the outer circumferential surface of said member being adapted to receive a strip of material to be fastened about and upon said outer circumferential surface, and superimposed portions of said strip of material being adapted to be inserted through said passageway into said bore at a side of said cam, the cam including an external cylindrical surface thereof adapted to be rotated in proximate relation to the internal cylindrical surface of said bore to pull said superimposed portions of the strip of material inwardly of said bore thus to cause said strip to be made taut upon said outer circumferential surface, and said external and internal cylindrical surfaces in cooperation with each other being adapted to cause said superimposed portions of the strip removably to be fastened in said holder, a plurality of spaced apart, longitudinally extending rows of spaced apart protuberances upon the external cylindrical surface of said cam, and a plurality of spaced apart, circumferentially extending protuberances upon said internal cylindrical surface provided by said bore, said circumferentially extending protuberances being disposed at the side of said bore directly opposite said passageway and there being protuberances upon said external cylindrical surface at either side of and in spaced relation to a circumferentially extending protuberance upon said internal cylindrical surface and circumferentially extending protuberances upon said internal cylindrical surface at either side of and in spaced relation to a protuberance upon said external cylindrical surface.

9. A holder comprising a member providing an outer circumferential surface, said member including a bore providing an internal cylindrical

surface and there being a passageway leading from said outer circumferential surface to said bore, a cam adapted to be actuated within said bore, the outer circumferential surface of said member being adapted to receive a strip of material to be fastened about and upon said outer circumferential surface, and superimposed portions of said strip of material being adapted to be inserted through said passageway into said bore at a side of said cam, the cam including a shaft thereof concentric with the internal cylindrical surface of said bore and an external cylindrical surface thereof adapted to be rotated at spaced distance from said internal cylindrical surface less than a measurement representing the total thickness of said superimposed portions to pull the superimposed portions inwardly of said bore thus to cause said strip to be made taut upon said outer circumferential surface, and said external and internal cylindrical surfaces in cooperation with each other being adapted to cause said superimposed portions of the strip removably to be fastened in said holder, a plurality of spaced apart, longitudinally extending rows of spaced apart protuberances upon the external surface of said cam, and a plurality of spaced apart, circumferentially extending protuberances upon said internal surface provided by said bore.

10. A holder comprising a member providing an outer circumferential surface, said member including a bore providing an internal cylindrical surface and there being a passageway leading from said outer circumferential surface to said bore, a cam adapted to be actuated within said bore, the outer circumferential surface of said member being adapted to receive a strip of material to be fastened about and upon said outer circumferential surface, and superimposed portions of said strip of material being adapted to be inserted through said passageway into said bore at a side of said cam, the cam including a shaft thereof concentric with the internal cylindrical surface of said bore and an external cylindrical surface thereof adapted to be rotated at spaced distance from said internal cylindrical surface less than a measurement representing the total thickness of said superimposed portions to pull the superimposed portions inwardly of said bore thus to cause said strip to be made taut upon said outer circumferential surface, and said external and internal cylindrical surfaces in cooperation with each other being adapted to cause said superimposed portions of the strip removably to be fastened in said holder, a plurality of spaced apart, longitudinally extending rows of spaced apart protuberances upon the external surface of said cam, and a plurality of spaced apart, circumferentially extending protuberances upon said internal surface provided by said bore, said circumferentially extending protuberances being disposed at the side of said bore directly opposite said passageway and there being protuberances upon said external cylindrical surface at either side of and in spaced relation to a circumferentially extending protuberance upon said internal cylindrical surface and circumferentially extending protuberances upon said internal cylindrical surface at either side of and in spaced relation to a protuberance upon said external cylindrical surface.

CARL F. ANDERSON.
